UNITED STATES PATENT OFFICE.

EZEKIEL H. HOLLAND, OF BYRON, GEORGIA.

REFRIGERATOR.

Application filed March 18, 1920. Serial No. 366,862.

To all whom it may concern:

Be it known that I, EZEKIEL H. HOLLAND, a citizen of the United States, residing at Byron, in the county of Houston and State 5 of Georgia, have invented a certain new and useful Improvement in Refrigerators, of which the following is a full, clear, and exact description, reference being had to the accompanying drawings.

10 This invention relates to refrigerator construction, and is illustrated as embodied in a vending machine for bottled goods.

An object of my invention is the arrangement of an article carrier and an ice receiving tank within a suitable receptacle, with provision of a circulatory air passage 15 through the tank and carrier, with means for deflecting air currents over the ice and between the articles to be cooled. A more 20 specific object is the provision of an insulated receptacle adapted to have supported therein a plurality of article carriers, with an ice tank, having an interior air passage-way, supported within certain of said carriers, and above other carriers, and deflecting 25 surfaces carried by the tank and receptacle for causing currents of air circulating upwardly through the passage to pass over the ice in the tank in proximity thereto and down 30 through and around the goods within the carrier.

Features of the invention include, in addition to the above noted provisions for circulating the cooling air, the arrangement of 35 the insulation of portions of the tank and carriers, and the provision of a precooling chamber below the carriers.

The above and other features and objects 40 will be more fully hereinafter explained, and the essential characteristics of the invention will be summarized in the claims.

A preferred embodiment of my invention is illustrated in the accompanying drawings, in which Fig. 1 is a front elevation of my 45 refrigerator apparatus embodied in a bottle vending machine; Fig. 2 is a vertical section through the receptacle with parts in elevation; Fig. 3 is a vertical section through the lower carrier shown in Fig. 2; Fig. 4 is a 50 plan of the same; Fig. 5 is a horizontal section through the ice tank and one of the upper carriers; Fig. 6 is a horizontal section through the actuating means for the carriers; Fig. 7 is a horizontal section on the 55 line 7-7 of Fig. 2; and Fig. 8 is a detail

partially in vertical section showing means for supporting and guiding the carrier gears.

My invention is illustrated in its application to a bottle vending machine somewhat 60 similar to those shown, described and claimed in my applications filed November 22, 1918, and March 12, 1920, Serial Numbers 263,647 and 365,278, respectively. It will be understood, however, that the invention 65 is not limited to any particular character of goods or method of dispensing the same, but is adaptable to effect and maintain efficient and economical refrigeration of goods of general description, arranged with- 70 in a cooling chamber.

In the drawings the numeral 10 designates a receptacle adapted to contain an inner ice tank and one or more carriers for articles, the refrigeration of which is to be effected 75 and maintained. In the vending machine illustrated the receptacle 10 is provided with superposed rotatable carriers in the interior and with exterior castings 12 arranged in echelon on its walls each having a doorway 80 closed by a door 14, and coin controlled actuating means 15, whereby the door may be unlocked and the carriers moved to bring the goods contained therein successively into 85 juxtaposition with the doorway. The receptacle is shown mounted on legs 17, which support it at a convenient height, and by providing the doors and operating mechanism for each carrier in echelon, the several carriers are all conveniently accessible at one 90 time.

The receptacle 10 is preferably cylindrical and has inner and outer sheet metal walls, 20 and 21 respectively, separated by cork or other heat insulating material 22. The bottom of the receptacle is shown consisting of a wooden disk 24 closely fitting within the lower end of the outer wall 21. Spaced from the disk 24 by a disk of suitable insulation 25 is an interior disk 26 constituting an inner 100 bottom wall which may be secured to the inner cylindrical wall 20 in any suitable manner.

Within the receptacle 10 there is supported an interior tank 30 adapted to receive 105 ice. The tank 30 is also preferably cylindrical and of a size providing between its outer wall and the inner wall 20 of the receptacle 10, space adapted to receive annular carriers 32, supported by the inner wall of 110

the receptacle. Below the tank 30 there may be supported one or more somewhat similar carriers 33, one only being shown, and between the lower carrier 33 and the bottom 26 of the receptacle there is provided storage space which may constitute a pre-cooling chamber 35. This precooling chamber 35 is provided with a door 36 adapted to be locked as at 37, and may be used to receive the goods when distributed to the machine, or to receive a surplus after the carriers have been filled. When refilling the carriers in a manner hereinafter described, precooled goods from the chamber 35 are preferably used, thus avoiding the vending of uncooled goods immediately thereafter from the carriers.

Between the inner and outer walls of the receptacle vertical supporting strips 40, preferably of metal, are provided. In the form shown, studs 41 are secured to these strips 40; they may be screwed through them and retained by nuts 42. Suitable rollers 44 are shown as mounted on the ends of the studs 25 projecting into the receptacle, and constitute anti-friction supports for the carriers 32 and 33.

The carriers shown are each provided at the bottom with means whereby they may be 30 rotated, comprising gears 46 having spur-teeth 47 adapted to mesh with pinions 48. The pinion comprises a part of the operating means 15 for each carrier. As shown in Fig. 8 the under surface of each gear is provided with an annular shoulder 49 near its periphery. The rollers 44 have flanges 45 engaging the shoulder 49, thereby providing guiding and centering means for the gears and carriers secured thereto.

40 The upper carriers 32 comprise top and bottom annuli 50, supporting between them annular series of outwardly-facing semi-cylindrical compartments 52, having vertical walls 53, each being adapted to contain 45 a bottle B. The carriers 32 are preferably mounted surrounding the ice tank and are adapted to be rotated around the tank 30 to bring fresh bottles, contained in the compartments 52, to their respective doorways 14. 50 The carrier 33 supported below the tank 30 comprises top and bottom disks 54, supporting between their outer periphery an annular series of compartments 52, similar to those on the carriers 32. The disks 54 are 55 provided with registering central openings occupied by a sleeve or tube 56, as shown in Fig. 3. The surface of the tube 56 and of the disks 54 within the ring of compartments 52 is preferably insulated as at 57.

60 While I have shown the carriers as rotatable, it will be understood that they might be stationary, as far as the refrigeration is concerned, or simply shelves might be substituted for them.

65 Around the top of the receptacle 10, se-

cured to the inner wall 20, as by screws 61, I provide a ring 62, whereby a top for the receptacle may be securely held tightly in place. The top comprises a member 64, having a central opening 65 therein, preferably 70 rectangular, to provide means of access to the ice tank 30. The member 64 may be secured to the receptacle as by bent-end bolts 66 passed therethrough engaging the underside of the ring 62, with suitable securing 75 nuts 67 provided on the outwardly projecting ends of the bolts. The projecting ends of the bolts through the nuts may be riveted over, if desired, to prevent removal of the top. The outer periphery of the member 64 80 is preferably octagonal for purposes of ornamentation and may be provided with a downward flange 63. Secured to the under-surface of the member 64 is a plate member 76, preferably of wood, spaced therefrom as 85 by insulation 77, with its outer periphery closely fitting the interior of the wall 20 of the receptacle, and its inner periphery comprising a rectangular opening in registry with the opening 65 in the top member 64. 90

The top 64 may be provided in its central portion over the ice tank 30 with removable covers for the convenient supplying of ice to the tank. I have shown the rectangular opening 65 in the top 64, provided with an 95 upstanding wall or rim 68, to which may be hinged as at 69 a flanged cover 70. Within the wall 68 and supported as on an inwardly extending flange or rim 72 is an auxiliary tight-fitting cover 74 to aid in preserving 100 the refrigeration. The cover 70 and top 64 are preferably of wood covered with sheet metal as at 75.

The ice tank 30 may be supported within the receptacle by a metal strap 80 bent into 105 U-shape and extending beneath the bottom of the tank 30 with its ends secured as at 81 to the under surface of the member 76 of the top. The top of the tank is open and is provided with an outward flange 85 extending 110 nearly to the inner wall 20 of the receptacle. This flange extends over the carriers 32, and for a purpose hereinafter explained, may be perforated at various points if desired. The central portion of the tank is provided 115 with an open ended vertical tube 87, extending from top to bottom, thus providing a central opening through the tank. The walls of the tube are preferably double and spaced apart by insulation 88. Above the 120 tube 87 and spaced slightly therefrom, I provide a baffle plate 90 which may be secured to the auxiliary cover 74.

The bottom of the ice tank 30 may be provided with a draining opening normally 125 closed by a plug 92, and a plug 93 may be employed for closing the drain pipe 94 in the bottom of the receptacle.

The use and operation of the device shown may be described as follows:—To fill the 130

carriers 32 and 33, the doors 14 may be unlocked by suitable means and the carriers supplied with filled containers B, preferably taken from the precooling chamber 35. Ice 5 is supplied to the tank 30 through the openings closed by covers 70 and 74. By reason of the flange 85 on the ice tank 30, and the top 64 being secured to the receptacle in a manner to prevent removal, the only means 10 of access to the carriers in the machine shown is through the doors 14, which a purchaser may unlock by insertion of a proper coin and operation of the mechanism 15.

By reason of the passageway provided by 15 means of the tube 87 in the ice tank 30 and the tube 56 in the carrier 33 below the tank, a current of relatively warm air may ascend continually through the center of the ice tank and be deflected by the baffle plate 90 20 over the open top of the tank 30 in close engagement with the ice contained therein, and then pass over the edge of the flange 85 or, if the latter is perforated, partly through the flange, downwardly around and between 25 the bottles in the carriers 32 and 33, near the edge walls of the receptacle, thus distributing the area over which it passes. The insulation of the lower carrier checks radiation and prevents the too rapid descent of 30 the cold air and tends to cause it to remain longer and circulate more thoroughly around and between the bottles, thus causing their heat to be efficiently absorbed and a high degree of refrigeration to be obtained. A continual circulation of the air upwardly 35 through the center of the carriers and ice tank and downwardly through the outer peripheries of the carriers into the precooling chamber, thus effects a rapid and effective 40 refrigeration of the goods contained in the carriers.

Having thus described my invention, I claim:—

1. In a refrigerator, a receptacle, an article support and an ice tank within the receptacle and located one over the other, a tubular vertical passageway through the ice tank, and an opening through the support in substantial registration with said passageway but terminating at a point spaced from said passageway.

2. In a refrigerator, a receptacle having insulated top and bottom and side walls, an ice tank mounted near the top of the receptacle, said tank having a vertical air passage therethrough, an article carrier mounted in the receptacle on the outer side of the tank, an insulated carrier mounted in the receptacle below the tank, said last named 50 carrier having an opening in substantial registration with the opening in the tank.

3. In a refrigerator, a receptacle, an article support, an ice tank of less diameter than the receptacle, open at the top, having 55 its side walls terminating short of the

top of the receptacle, and a vertical air passage through the ice tank, and means whereby air may circulate upwardly through the interior of the tank and support and then downwardly around the peripheries thereof.

4. In a refrigerator, a receptacle, an article support, an ice tank therein having its side walls spaced from the walls of the receptacle and terminating short of the top 70 of the receptacle, a vertical tubular member extending through said ice tank, and means whereby air may circulate upwardly through said tubular member and then downwardly over the sides of the tank and 75 around the article support.

5. In a refrigerator, a receptacle, a carrier supported therein, an ice tank of less diameter than the receptacle, said tank having the side walls thereof terminating short 80 of the top of the receptacle, and having a vertical air passage therethrough, a member extending outwardly from the top of said tank and over the carrier but spaced from the side walls of the receptacle, and 85 means whereby air may circulate upwardly through the vertical passage and thence across the ice tank over the top of the member and then downwardly around the articles in said carrier.

6. In a refrigerator, a receptacle, an article support and an ice tank within the receptacle, said tank being of less diameter than the receptacle and terminating short 90 of the top of the receptacle, a vertical passageway through the ice tank, an opening through the support in registration with the passageway, and means whereby air may circulate through the registering passageways, thence across the ice tank and 95 downwardly around the sides thereof and over the articles in said support.

7. In a refrigerator, a receptacle, an ice tank centrally supported in the upper portion thereof, a carrier surrounding the tank, 100 another carrier positioned below the tank, a central tubular passageway extending through the tank and carried therebelow, and means whereby air may circulate upwardly through said registering passageways, and thence across the top of the tank, 105 and then downwardly around the articles in said carriers.

8. In a refrigerator, a receptacle, a plurality of article carriers, an ice tank supported within the receptacle embraced by said carriers, said tank having a central vertical air passage, and means whereby air may circulate upwardly through the interior 110 of the tank and carriers, and then downwardly around the articles in said carrier.

9. In a refrigerator, a receptacle, an ice tank supported in the upper portion thereof, a carrier supported by the receptacle and surrounding the tank, a second carrier 115

supported by the receptacle below the tank, a precooling chamber below the second carrier, and means whereby air may circulate upwardly through the interior of the tank and carriers and downwardly around their peripheries to the precooling chamber.

10. In a refrigerator, a receptacle, an article support and an ice tank positioned one over the other within the receptacle, and substantially alined tubular vertical passageways through the ice tank and support, the walls of said passageway being insulated.

11. In a refrigerator, a receptacle, an article carrier and an ice tank within the receptacle, the carrier embracing the tank, an insulated vertical passageway through the tank, and a baffle plate above the passageway.

20 12. In a refrigerator, a receptacle, an ice tank supported therein, an article carrier supported below the tank, said carrier comprising an annular series of vertical compartment walls supported between top and bottom disks, an upwardly extending passageway through the disks, and insulation carried on the surface of the disks and the wall of the passageway.

13. In a refrigerator, a receptacle, an ice 30 tank suspended therein, a plurality of carriers supported from the inner wall of the receptacle, one of said carriers being below the tank and comprising spaced, insulated disks having article receiving com-

partments between their peripheries, and an upper carrier comprising annular members surrounding the tank, and having a plurality of article compartments between them.

14. In a refrigerator, a receptacle, a top 40 therefor, adapted to be secured to the receptacle, means depending from said top for supporting an ice tank, an ice tank therein, and a removable cover within an opening in the top for providing access 45 to the tank.

15. In a refrigerator, a receptacle, an ice tank suspended from the top thereof, said tank having an open top and an outwardly extending flange, a passageway extending 50 upwardly through the tank, and a baffle plate supported in the top of the receptacle above said passageway.

16. In a refrigerator, a receptacle, an ice tank supported in the upper portion thereof, 55 a plurality of carriers supported by the receptacle below the top of the tank, an interior air passageway extending upwardly through the tank and carriers, a precooling chamber below the tank and carriers, and 60 means whereby air may circulate between the top of the tank and the precooling chamber through the interior and around the exterior of the tank and carriers.

In testimony whereof, I hereunto affix 65 my signature.

EZEKIEL H. HOLLAND.
